CHAIR FITTING DEVICE

Sol Herbert Brown, San Francisco, Calif.

Application March 31, 1950, Serial No. 153,046

6 Claims. (Cl. 33—174)

1

This invention relates to a chair fitting device for use in obtaining the desired information for making chairs that will conform to the desires or physical characteristics of individual users, or for altering chairs to the same end.

The principal object of the invention is the provision of means for quickly, accurately, and easily obtaining the necessary information for making chairs that will conform to the desires or physical characteristics of individual users, or for altering chairs to the same end.

Heretofore, in making a chair to the individual order of a user, insofar as its utility is concerned, it has been necessary to merely approximate accomplishing the desires of such user by the relatively primitive method of blocking up, filling out or removing certain portions of an existing chair, supplemented by verbal instructions where deficiencies continue to exist. This procedure is prohibitively costly and the results leave much to be desired due to the impracticability of making certain adjustments.

Another method, and the one most commonly employed is for the user to try out an assortment of chairs in an effort to obtain one that may fit better than the others. This, of course, requires a large assortment of chairs and in the end the user must resort to verbal instructions for the changes to be made, with the result that the final chair that is produced seldom comes up to the expectation of the user, particularly where consideration is given to the cost involved.

With the present invention, each detail of the chair from the standpoint of fit and comfort as applied to the particular individual who will use the chair, is quickly and accurately determined and the chair that is made in accordance with the data obtained from use of the said invention will be entirely free from any guesswork as to size, fit, tilt, different relationships between such parts as the seat, back, arms and the other details that may enter into making an individually fitted chair.

Other objects and advantages will appear in the drawings and description.

In the drawings,

Fig. 1 is a top plan view of a preferred form of the invention, one corner being broken away and in section to disclose certain structure.

Fig. 2 is a side elevational view of the device shown in Fig. 1 as seen from the side provided with the adjusting wheels seen in Fig. 1.

Fig. 3 is an enlarged fragmentary sectional view taken along line III—III of Fig. 1.

Fig. 4 is an enlarged fragmentary sectional view taken along line IV—IV of Fig. 1.

2

Fig. 5 is a fragmentary enlarged sectional view taken along line V—V of Fig. 3, the inner upholstering in the seat portion being omitted for clarity.

5 Fig. 6 is an enlarged sectional view of one of the arm supports as seen along line VI—VI of Fig. 5.

Fig. 7 is an enlarged fragmentary sectional view of a bearing for the arm support as seen 10 along line VII of Fig. 5.

Fig. 8 is an enlarged fragmentary sectional view of another bearing for the arm support as seen along line VIII of Fig. 5.

Fig. 9 is a top plan view of the rear of the seat 15 adjusting mechanism (one gear being in cross section) and the back of the seat being indicated in dot-dash lines.

Fig. 10 is a rear view of the seat adjusting mechanism as seen from the back of the seat, 20 the latter being indicated in dot-dash lines. Line x—x of Fig. 4 indicates the point of view.

Fig. 11 is a fragmentary sectional view taken 25 along line XI—XI of Fig. 3 with the foot rest omitted, but with its outline indicated in dot-dash lines.

Fig. 12 is a fragmentary sectional view taken along line XII—XII of Fig. 11.

Fig. 13 is an enlarged fragmentary sectional view of one of the back adjusting means as seen from line XIII—XIII of Fig. 10.

30 Fig. 14 is an enlarged fragmentary view of a portion of the adjusting means as seen from line XIV—XIV of Fig. 10.

Fig. 15 is a fragmentary enlarged sectional view of part of one of the control or adjusting 35 means on line XV of Fig. 3.

Fig. 16 is a semi-schematic sectional view showing the various seat adjustments in dot-dash line with the seat and back being indicated in full line in one position.

40 In detail, the invention as illustrated in the drawings comprises an upholstered back 1 (Fig. 1) and seat 2, arm rests 3, and foot support 4. These parts are movable relative to each other. The upholstering or padding in the seat and back 45 and arm rests may be of any conventional type. It is not removed or altered in making seat and back adjustments and the seat and back frames are adapted to support any type of conventional upholstery.

50 The seat frame includes a pair of parallel opposed vertically disposed frame members 5 having oppositely outwardly opening horizontal parallel channel members 6 secured thereto along the upper edges of said frame members 5 (Figs. 4, 5) projecting downwardly from the lower for-

55

ward corners of said frame members 5 are aligned bearings 7 through which a horizontal shaft 8 extends on which said bearings are pivotally supported. This shaft is rotatably carried in bearings on frame members 10 of the chair (Figs. 5, 11).

From the above it will be seen that the chair seat frame is pivotally supported at its forward end on shaft 8 for swinging from full line position 2 of said seat in Fig. 16 to dot-dash line position 2' and to any degree of incline between said positions 2, 2'.

It is to be understood that the depth of said seat (front to rear) is sufficient to properly seat persons of different sizes. As will be later explained, the back is preferably adapted to move over the seat from front to rear so as to enable the seat and back to be adjusted relatively to persons having widely different physical characteristics.

The adjusting of the inclination of the seat between positions 2, 2' (Fig. 11) is accomplished by the provision of a pair of gear segments 12 secured to the rear ends of the seat frame members 5 (Fig. 4). Said segments extend upwardly and the teeth are along lines concentric with the pivot shaft 8. Pinions 13 secured on a horizontal shaft 14, that in turn is journalled in bearings on rigid frame members 15 (Fig. 3) have their teeth in mesh with the teeth of the gear segments 12.

The shaft 14 is provided with a sprocket wheel 15' over which a sprocket chain 16 extends. The chain 16 also extends over a sprocket wheel 17 (Fig. 5) that is secured on rotatable pivot shaft 8.

The shaft 8 also has a worm wheel 18 (Fig. 3) secured thereon, which worm wheel is in mesh with a worm 19. Worm 19 is secured on a vertical shaft 20, said shaft 20 being journalled at its ends in bearings 21 secured to the rigid frame of the device. The upper end of shaft 20 has a bevel gear 22 secured thereto, the teeth of which are in mesh with the teeth of a bevel gear 23' that is secured on one end of a horizontal shaft 23. This shaft 23 in turn is rotatably supported on the rigid frame of the machine which includes a control box 25 (Figs. 1, 2) at one side of the seat. The end of shaft 23 opposite bevel gear 23' extends out of the outer vertical side of the control box and has a hand wheel 24, secured thereto for rotating shaft 23 in either direction. A worm 26 on shaft 23 is in mesh with a worm wheel 27 (Fig. 1) that in turn is on a short vertical shaft 28. The upper end of shaft 28 extends through the upper side of the control box 25 and an indicator arm or needle 29 on the upper exposed end of shaft 28 is adapted to scan a coded dial 30, or to point to indicia on a dial around the axis of shaft 28.

Normally, when the seat 2 is horizontal, the indicator arm or needle 29 may, for example, be directed toward a graduation that reads zero or the equivalent. Upon rotating the hand wheel 24 in a direction for causing the pinion 13 to lower the rear end of seat 2, the needle 29 will progressively move to and past graduations that may be designated by any desired symbols, and which symbols may read directly in degrees of angle between the seat and vertical or horizontal, or may provide for any other desired reading. Whatever the reading or symbol is, it is one from which the angular position of the seat may be readily determined and code markings may be used for this purpose and translatable into the information desired.

From the above, it is seen that preferably, the seat itself is not moved forwardly or backwardly, but is merely tilted about a horizontal axis, as desired.

The channel members 6 at opposite sides of the seat frame project rearwardly of the side frame members 5 for a substantial distance and terminate rearwardly of the seat and of the back when the latter is in its most rearward position.

Within each channel member 6 is a horizontal screw 31, each screw being rotatably supported and held at its ends in bearings 32 secured to the said channel members (Fig. 4). The back frame carries a bracket 33 rigid therewith at each side of the seat, and each bracket is provided at its rear end with an internally threaded projection 34 through which the screw 31 threadedly extends. The forward end of each bracket 33 has a similar projection 35 through which screw 31 slidably extends and upwardly projecting lugs 36 on the forward ends of brackets 33 have axially aligned openings for axially aligned pivots 37 that connect the back with the brackets. Thus, the back is adapted to swing about the pivots 37, and said pivots are positioned adjacent the forward side of the back as seen in Fig. 4.

By rotating the screws 31, the brackets 33, and consequently the back 1, will be moved either toward or away from the front edge of seat 2 according to the direction of rotation of said screws.

The rear ends of screws 31 each carry a bevel gear 38 (Figs. 10, 13). A pair of bevel gears 39 secured on a horizontal shaft 39' that extends between gears 38 have their teeth in mesh with the teeth of gears 38. Shaft 39' is journalled in bearings 40 that are secured to a cross frame member 41 that in turn connects the rear ends of channel members 6.

One of the ends of shaft 39' has a sprocket wheel 42 secured thereto (Fig. 10). A sprocket chain 43 connects said wheel 42 with a sprocket wheel 44 that is in turn secured on one end of a sleeve 45 (Fig. 5) that is rotatable on the pivot shaft 8. The other end of sleeve 45 has a sprocket wheel 46. A chain 47 connects sprocket wheel 46 with a sprocket wheel 48 (Fig. 3) that is on a shaft 49. Said shaft 49 is parallel with and similar to the shaft 23' that has hand wheel 24 secured thereto, and a similar hand wheel 50 is secured on shaft 49 for rotating the latter. This hand wheel 50 is connected with an indicator 51 (Fig. 1) that is on a vertical shaft 52 by worm gears (not shown) that are identical with the gears 26, 27 that are respectively on shafts 23, 28. Indicator 51 scans or moves around a dial 53 having any desired symbols thereon for indicating the relationship between the back and the forward edge of the seat.

By the foregoing explanation, it will be seen that the seat 2 is tilted by actuation of the hand wheel 24, and the back will move downwardly or upwardly with the seat when the latter is tilted. By rotation of hand wheel 50, the back 1 may be moved toward and away from the forward edge of the seat 2, and this movement may be effected at any degree of inclination of the seat, as well as when the seat is tilted. In fact the seat may be tilted simultaneously with movement of the back.

In order to swing the back to different angular positions relative to the seat, a pair of similar segmental gears 55 are secured to the back

of the seat adjacent each of its side edges (Figs. 4, 13), and upstanding members 56, 57 on brackets 33 have aligned bearings in their upper ends in which the ends of a shaft 58 is rotatable.

Below, and parallel with shaft 58 is a second shaft 59 that is also supported at its ends for rotation in members 56, 57. Sprocket wheels 60, 61 respectively secured on shafts 58, 59 are connected for rotation together by a sprocket chain 62. The sprocket wheel and chain are diagrammatically indicated in dot-dash line in Fig. 13 in order to clearly show how the lower ends of the segmental gears 55 extend over shaft 59 in order to provide for added movement of said gears. Pinions 63 secured on shaft 58 (Fig. 10) have their teeth in mesh with the teeth of the segmental gears 55.

The end of shaft 59 opposite the sprocket wheel 61 extends through the upstanding member 57 and has a worm wheel 65 secured thereto. The teeth of worm wheel 65 are in mesh with the teeth of a worm 66 that is secured on a shaft 67, the latter being journaled for rotation in bearings on member 57 (Fig. 14).

A bevel gear 69 is secured on one end of the shaft 67, and the teeth of said gear are in mesh with the teeth of a bevel gear 70 that is secured on shaft 71.

Shaft 71 is journaled for rotation in bearings secured to the cross frame 41 and the end of said shaft opposite gear 70 has a sprocket wheel 72 secured thereto (Fig. 10). This sprocket wheel is connected by a chain 73 with a sprocket wheel 74 that is secured on one end of a sleeve 75. Sleeve 75 is in turn rotatable on the sleeve 45 that, in turn, is rotatable on pivot shaft 8. Also secured on sleeve 75 is a sprocket wheel 77 (Fig. 5). This sprocket wheel 77 is connected by a chain 78 (Fig. 3) with a sprocket wheel 79. Sprocket wheel 79 is secured on a shaft 80 that is identical with shafts 28, 52 on which hand wheels 24, 50 are respectively secured. A hand wheel 81 is secured on one end of shaft 80 and is alongside wheel 50 (Figs. 1, 2). Said shaft 80 is connected by worm gearing (not shown) with a vertical shaft 82 that in turn carries an indicator 83 adapted to scan or move around a dial 84 having suitable symbols thereon, coded or otherwise, for designating the degree of inclination of the back 1 when wheel 80 is rotated.

It is pertinent to note (Fig. 16) that the back 1 may be inclined forwardly at its upper end relative to vertical when the seat is horizontal. This permits the back to be adjusted to vertical position when the seat is inclined, which would not otherwise be possible, and there are some instances where it is desirable that the back 1 be disposed at an acute angle relative to vertical, which is usually when the seat is inclined.

In connection with the back tilting means, it is pertinent to note that the back may be tilted by revolving hand wheel 81 either simultaneously with making the other adjustments, or independently of the means for making said other adjustments. It is immaterial whether the seat is level, or tilted, or whether the back has been moved forwardly or rearwardly. At any time the back may be tilted.

In Fig. 5 it will be seen that the arm rests 3 are each carried on the inner end of an arm 85. These arms 85 extend toward each other from opposite sides of the seat and above the latter, therefore their "inner" ends are their adjacent ends that are nearest each other.

The arm rests are identical, hence a descrip-

tion of one, including its supporting and operating means, will suffice for the other, although, as will be later explained, more in detail, a common means is connected with the arm rest elevating means for simultaneously actuating them for corresponding upward and downward movement, and another common means is connected with them for simultaneously moving the arm rests toward and away from each other.

At each side of the seat 2 are a pair of vertically disposed, rigid, guide members 86 (Fig. 3) and between each of said pairs is a vertical slide 87 that is held on said guides for vertical movement up and down.

Each slide 87 carries a bracket 89 (Fig. 5) that is rigid therewith. Brackets 89 extend toward each other from the oppositely facing sides of the slides that are at opposite sides of the seat, and each bracket 89 carries horizontally disposed slide supports 90 at the upper end thereof. Slide supports 90 extend toward each other from said upper ends of the brackets 89.

Carried by each of the said slide supports 90 is a slide 91 (Fig. 6), and each slide 91 carries an arm support 92 for each of the arms 85 that has the arm rest 3 thereon.

Each arm support 92 is horizontally elongated in a direction parallel with the horizontal longitudinal axis of the seat and with each arm rest 3, the latter extending in a direction from the front to rear of the chair in the usual manner for arm rests.

Each arm support comprises a horizontal, elongated base 93 lower row of balls 94 in a straight race that extends longitudinally of said support (Figs. 6, 7), and spaced above said row in an overhead hold-down strip 95 that is secured at its ends to the base by end pieces 96 (Figs. 6, 7). The arm 85 is generally in the form of an inverted channel strip of substantial width, and passes between the hold down strip 95 and the row of balls 94 transversely thereof. At the point where each arm 85 crosses the row of balls, it is provided with a cross rib 97 extending between the downwardly extending sides of the channel strip forming each arm support 85. The lower surface of said rib is recessed to provide an upper race for the balls 94 and is supported on balls in said row for movement of the arm support longitudinally of said row.

The outer end of each arm support 85 extends below a flange 98 that is spaced above the slide 91 and that is secured to said slide in a position spaced laterally from base 93, but parallel therewith (Figs. 5, 8). The lower side of flange 98 is longitudinally recessed to provide a race for a row of balls 100, and the upper side of the outer end of each arm 85 is also grooved or recessed to provide a lower race for said balls. A strip 101 spaced below the outer end of each arm 85 is secured at its ends to flange 98 for retaining the outer ends of said arms from moving downwardly a sufficient distance to enable the balls to fall out of the recess.

Balls 94 and balls 100 are respectively held by conventional cages or spacers 102, 103 in spaced relation in their races.

From the foregoing, it will be seen that the arm rests 3 may easily and readily be moved longitudinally in directions toward and away from back 1. No mechanism is required for this movement, inasmuch as the arm rests on chairs are practically always horizontal and will stay in whatever position they are moved. This manner of movement of the arm rests is also highly de-

sirable so there will be no possible blocking of movement of the back by said rests when said back is being adjusted. If the arm rests were locked in position, it would, in many instances, be necessary to unlock them before changing the position of the back. This would be undesirable, whereas by enabling the user to freely move the arm rests forwardly or backwardly when seated in the chair, the back is free to move to any position, even were the ends of the arm rests in engagement with the back.

Elevation of the arm rests is provided for by providing for vertical movement of the slide 87.

Secured to each of the oppositely outward-facing sides of vertical slides 87 is a threaded member 105 through which extends a vertical screw 106 in threaded engagement with the threads in each member (Fig. 3). Each screw 106 is rotatably secured at its lower end in a bearing on the base 107 of the device, and the lower end of each screw has a spiral gear 108 secured thereon, the teeth of which spiral gears are, in turn, in mesh with the teeth of worm gears that are respectively secured on the ends of a horizontal shaft 110 (Fig. 5). Bearings secured to base 107 or to any rigid part of the device may rotatably support shaft 110.

Also secured on shaft 110 is a sprocket wheel 111 (Fig. 3) that is connected by a chain 112 with a sprocket 113 on a horizontal shaft 114. This shaft 114 is identical with shafts 49 and 80 and is parallel therewith. Said shaft 114 has a hand-wheel 115 secured on one end and which wheel is one of the row of hand wheels that is along the lateral side of the control box 25 (Figs. 1, 2). A worm gear connection connects shaft 114 with vertical shaft 116 that has an indicator 117 thereon. This indicator scans or moves around a dial 118 that is provided with symbols adapted to indicate, or to be translated for indicating, the height of the arm rests relative to the seat or relative to any other desired part.

By rotating the hand wheel 115 in one direction or the other the arm rests will be simultaneously moved up or down, and this movement may be effected simultaneously with the other adjustments or by itself irrespective of the relative positions of the other parts of the device.

The horizontal slides 91 on which the arm rests are carried, each has on its underside a downwardly projecting threaded member 120 (Fig. 5). Horizontal axially aligned screws 121 respectively extend through these members in threaded engagement therewith. The inner adjacent ends of these screws terminate at points adjacent the opposite sides of the seat so as not to interfere with movement of the seat and back.

The outer ends of screws 121 are journalled in bearings suitably secured to the frame of the control box 25, and each outer end has a spiral gear 122 secured thereto.

The teeth of each spiral gear 122 are in mesh with the teeth of a spiral gear 123 that is splined on a vertical shaft 124 (Fig. 3), the said gear 123 being rotatably carried between bearings that are in turn secured to each vertical slide 87.

The lower end of each shaft 124 is supported for rotation in a bearing on base 107 and also secured on the lower end of each shaft 124 is a spiral gear 125, the teeth of which are in mesh with the teeth of worm gears 126 on the ends of a horizontal shaft 127 that is rotatable in bearings secured to base 107.

Shaft 127 extends at one end into the lower end of the control box 25, and said end has a

sprocket wheel 128 secured thereon. Said wheel 128 is connected by a chain 130 with a sprocket wheel 131 that is, in turn, secured on one end of a shaft 132. This shaft 132 is identical with the shafts 80, 115 and is parallel therewith. A hand wheel 133 is secured on one end of shaft 132 and a worm gear connection identical with the indicator controls previously described, connects shaft 132 with a vertical shaft 135 on the upper end of which is an indicator 137 that is to move around a dial 138 in one direction or the other according to the direction of rotation of the hand wheel 133. The symbols on dial 138 are such as to designate the spacing between the arm rests.

When the hand wheel 133 is rotated in one direction, the arm rests will be simultaneously moved toward each other, and when said wheel is rotated in the opposite direction, they will be moved apart. These movements may be simultaneous with the movement of any one or more of the other parts of the chair.

The foot rest 4 is movable vertically up and down relative to the seat. In this manner the desired elevation of the seat from the floor may be determined without moving the seat.

Said foot rest 4 is a horizontal rectangular platform (Figs. 1, 11, 16) that is provided with a nut 140 (Fig. 12) at each of its four corners. Threadedly extending through each nut 140 is a vertical screw 141. The upper ends of these screws project above the foot rest and are journaled for rotation in bearings 142 secured in any suitable manner to the frame of the machine. The lower ends of said screws are also journalled for rotation in bearings 143 that may be secured in any suitable manner to base 107.

A sprocket wheel 144 is secured to the lower end of each vertical screw 141, said wheels being coplanar, and a sprocket chain 145 extends around the four vertical shafts and in engagement with said sprocket wheels 144 so that movement of said chain in one direction or the other will cause simultaneous rotation of said screws.

This chain extends into the control box 25 and around a sprocket wheel 146 (Fig. 11) that is secured on the lower end of a vertical shaft 147 that is in the control box 25 (Figs. 1, 3). The said shaft 147 is journalled for rotation in upper and lower bearings 148, 149 that are secured to the frame of the machine.

On the upper end of shaft 147 is provided a bevel gear 150, the teeth of which are in mesh with the teeth of a bevel gear 151 that is in turn secured on a horizontal shaft 152. The outer end of shaft 147 projects from a side of the control box and has a hand wheel 153 secured thereto, while the opposite end of said shaft has a worm 154 secured thereto. The teeth of worm 154 are in mesh with the teeth of a worm 155 that is secured on the lower end of a vertical shaft 156. The upper end of shaft 156 has an indicator needle 157 that is adapted to move around a dial 158, which dial has suitable symbols thereon for designating the distance between the top of the seat and the foot rest. By rotating the hand wheel 153 in one direction or the other the foot rest will be moved up or down.

Referring to Fig. 16, it will be seen that the hand wheels 153, 24, 50, 81, 115, and 133 (indicated in dot-dash lines) are in a horizontal row along one lateral side of the control box, and the height of these wheels is such that an operator standing beside the box can readily read the dials that are directed upwardly on the upper

side of said box, and can also easily manipulate the hand wheels. Also such operator can readily see the seat parts so as to observe their relationship to each other and to a person seated in the chair.

By rotation of the hand wheel 153 in one direction or the other the foot rest may be moved between the full line elevated position seen in Fig. 16 and the lowered dot-dash line position 160, and it will stay in any position of adjustment irrespective of the downward force placed on the foot rest.

By rotation of hand wheel 24 in one direction or the other, the seat may be tilted about the pivot 8 between the horizontal full line position (Fig. 16) and the inclined dot-dash line position 161. In this instance the seat will also stay in any adjusted position due to the worm gear connections in the adjusting means.

By rotation of hand wheel 50 in one direction or the other the back 1 will be moved forwardly and backwardly between the rearmost full line position seen in Fig. 16 to the most forward dot-dash line position 162. The back is locked in any position of adjustment irrespective of the force that the person seated in the chair may apply to the back.

By manipulation of hand wheel 81 the back of the seat may be swung between the inclination seen in full line in Fig. 16 and the most forwardly inclined position 164 indicated in dot-dash line. The back will be locked in any position.

By manipulation of hand wheel 115, the arm rests will be moved up and down between the maximum height indicated in full line in Fig. 16 and the minimum height, indicated by dot-dash lines 165 (Figs. 5, 16).

By manipulation of hand wheel 133 the arm rests will be moved toward and away from each other between the full line position 3 (Fig. 5) and dot-dash line position 166.

As already mentioned, the arm rests may be moved longitudinally of the chair when they are in any position.

It is to be understood that the invention is not intended to be necessarily restricted to precise details of construction as herein specifically described. The illustrations and description show a preferred form of the invention.

By use of the chair, practically any fit may be quickly, easily and accurately made, and from the data obtained, a chair may be made to order in the desired style, and such chair will properly fit the body of the user.

I claim:

1. A chair fitting device comprising a rigid frame, a seat having a front edge, a back having a lower edge, pivot means respectively supporting said seat and said back for swinging about horizontal parallel axes respectively adjacent said front edge and said lower edge, seat and back actuating means for swinging said seat and said back about said axes including a pair of intermeshed worm gears respectively for said seat and said back providing means for locking said seat and said back at any position in their movement about their respective axes, a pair of arm rests spaced above said seat, means supporting said arm rests on said frame for vertical movement toward and away from said seat, movable means connecting said arm rests for said vertical movement simultaneously, and a single control mechanism connected with said last mentioned movable means for causing said vertical

movement upon actuation of said single control means.

2. A chair fitting device comprising a rigid frame, a seat having a front edge, a back having a lower edge, pivot means respectively supporting said seat and said back for swinging about horizontal parallel axes respectively adjacent said front edge and said lower edge, seat and back actuating means for swinging said seat and said back about said axes including a pair of intermeshed worm gears respectively for said seat and said back providing means for locking said seat and said back at any position in their movement about their respective axes, a pair of arm rests spaced above said seat, means supporting said arm rests on said frame for vertical movement toward and away from said seat, movable means connecting said arm rests for said vertical movement simultaneously, and a single control mechanism connected with said last mentioned movable means for causing said vertical movement upon actuation of said single control means, said movable means including stationary vertical screws rotatable about spaced vertical axes respectively adjacent each arm rest and vertically movable slides on said frame threadedly connected with said screws for movement along the latter upon rotation of said screws, said arm rests being secured to said slides for movement therewith, and said single control mechanism including means connecting said screws for simultaneous rotation.

3. A chair fitting device comprising a rigid frame, a seat, a back and arm rests, guide members at opposite sides of said seat, arm rest supports carrying said arm rests supported on said guide members for movement up and down, a mechanism connecting said arm rest supports for so moving said arm rests simultaneously, manually actuatable means connected with said mechanism for actuation thereof, members supporting said arm rests on said arm rest supports for horizontal movement toward and away from each other, driving means connecting said members for simultaneous movement toward and away from each other, and manually actuatable means connected with said last mentioned driving means for so moving said last mentioned members.

50 4. A chair fitting device comprising a rigid frame, a seat, a back and arm rests, guide members at opposite sides of said seat, arm rest supports carrying said arm rests supported on said guide members for movement up and down, a mechanism connecting said arm rest supports for so moving said arm rests simultaneously, manually actuatable means connected with said mechanism for actuation thereof, members supporting said arm rests on said arm rest supports for horizontal movement toward and away from each other, driving means connecting said members for simultaneous movement toward and away from each other, and manually actuatable means connected with said last mentioned driving means for so moving said last mentioned members, bearings supporting said arm rests on said members for reciprocable movement at right angles to their direction of movement toward and away from each other at any degree of elevation of said arm rests and at any degree of movement toward and away from each other.

5. A chair fitting device comprising; a rigid frame, a seat frame, a seat on said frame having a forward edge and a rear edge, a horizontal pivot securing said seat frame to said rigid frame

for tilting said seat frame relative to horizontal and vertical, a back frame, a support on said seat frame movable therewith supporting said back frame on said seat frame for horizontal reciprocal movement of said back frame relative to said seat frame toward and away from said forward edge, pivot means securing said back frame to said support adjacent to said rear edge and to the opposite sides of said seat for tilting said back frame relative to said seat frame, arm rests, guide members rigid relative to said rigid frame at opposite sides of said seat frame and an arm rest support carrying each arm rest supported on each guide member for vertical movement independently of said seat frame, separate manually actuatable mechanisms respectively connected with said seat frame and with said back frame for separately tilting said seat frame on its pivot and for moving said seat frame horizontally and for tilting said back frame on its pivot means, driving elements connecting said arm rest supports for simultaneous movement up and down and manually actuatable means connected with said elements for causing said last mentioned movement independently of said 25 separate manually actuatable mechanisms.

6. In a chair fitting device having a rigid frame and a seat frame having a seat thereon and a back frame having a back thereon; a horizontal pivot supporting said seat frame for 30 tilting movement relative to horizontal and vertical about the axis of said pivot, pivot means securing said back frame to said seat frame for swinging movement of said back frame about a horizontal axis parallel with said first mentioned axis and relative to said seat frame, a foot rest, means supporting said foot rest for movement up and down as desired, arm rests, guide members

10
15

at opposite sides of said frame, arm rest supports carrying said arm rests and supported on said guide members for up and down movement, a control box at one side of said rigid frame, separate mechanisms extending from said control box to said seat frame, back frame and foot rest for selectively actuating them as desired for their respective movements as desired, and an arm support actuating mechanism connected with said arm supports and extending to said control box for simultaneously moving said arm rests up and down independently of said seat frame and said back frame, manually actuatable elements on said control box connected with each of said separate mechanisms and with said arm support actuating mechanism for manually actuating them independently of each other.

SOL HERBERT BROWN.
